UNITED STATES PATENT OFFICE.

GEORGE W. KENNINGTON, OF BROOKLYN, NEW YORK.

SELF-SEATING DOOR-HANDLE.

1,337,918.

Specification of Letters Patent. Patented Apr. 20, 1920.

Application filed October 17, 1919. Serial No. 331,400.

To all whom it may concern:

Be it known that I, GEORGE W. KENNINGTON, a citizen of the United States, and a resident of the city of New York, borough 5 of Brooklyn, in the county of Kings and State of New York, have invented a new and Improved Self-Seating Door-Handle, of which the following is a full, clear, and exact description.

10 This invention relates generally to a new and improved door handle, particularly adapted for use in connection with sidewalk, trap, or other doors, which are usually arranged in a substantially horizontal position.

15 Heretofore handles used in connection with such doors have been connected to the upper side of the door and have been so constructed and arranged as to present a 20 projection above the door, which is objectionable because in the case of sidewalk doors, persons may be tripped thereby.

25 One of the objects of this invention is to provide a handle particularly adapted for use on doors occupying a substantially horizontal position, which is simple in construction, inexpensive to manufacture, and which is self-seating forming a substantially watertight joint and laying substantially flush 30 with the top of the door when not in use.

35 The above objects are accomplished by providing a door handle having a stem, a portion of which is tapered, and a substantially flat mushroom head at the upper part 40 thereof adjacent to the tapered portion, there being provided at the end of the stem a means to permit limited movement of the handle relative to the door. An opening is provided in the door or other body with 45 which the handle is used having a beveled or tapered seat corresponding with the bevel or taper of the stem. Preferably the under surface of the head is recessed so as to form an annular space between the outer edge of the handle and the stem. If desired, the upper exposed side of the handle is preferably provided with a roughened surface.

50 Other objects and advantages will be apparent from the following description and the accompanying drawings, in which similar characters of reference designate like parts in the several views.

Figure 1 is a view showing the application of the handle to sidewalk doors.

Fig. 2 is an enlarged sectional view looking in the direction of the arrows and taken on the line 2-2 of Fig. 1.

Fig. 3 is a vertical elevation of the handle showing the roughened upper surface.

Fig. 4 is a bottom plan view of Fig. 3.

In the drawings showing one of the preferred forms of the invention the handle is there shown as comprising a downwardly extending stem 1, which is tapered throughout a portion of the length thereof, there being shown, in the preferred form, a head or handle portion 2 of a mushroom shape. If the handle is used in connection with sidewalk doors 3, 4, as shown in Fig. 1, said doors will occupy a substantially horizontal position.

In applying a handle the door 3 will be provided with an opening 5 having a beveled or tapering seat 6 extending therearound, the said taper corresponding to the taper of the stem 1. When the stem 1 is positioned on the tapered seat of the door 3, the tapered stem portion of the handle is preferably located conveniently under the head 2 of the handle, and the outer rim 7 so of the handle is so positioned relative to the upper surface 8 of the door that when the tapered portion of the stem is positioned in the tapered seat of the door, the outer rim will rest upon the upper surface of the door 8 so that there will be formed between the outer portion of the handle and the tapered seat of the door an annular space. There is thus provided two joints which serve to prevent moisture and water from finding its way to the inner side of the door, one between the upper surface of the door 8 and the rim 7 of the handle, and the other between the stem 1 and the tapered seat 6.

Any suitable means may be provided to permit a limited upward movement of the stem sufficient to permit the handle 2 to be grasped, for example, by the insertion of the fingers between the under side of the handle 2 and the door 3. In the preferred construction, a nut 9 and washer 10 is provided for this purpose, the latter being held in place by the nut 9 which is threaded on the end of the stem 1. Of course, it is understood that the washer will be of a larger size than the opening 5 to prevent the entire withdrawal of the stem from the opening when the handle 2 is grasped to

move the door. It is, of course, understood that any other suitable means may be provided for this purpose.

If it is desired to open the door, it is only necessary to grasp the handle 2, preferably a distance sufficient to permit the fingers to be inserted between the under side of the handle and the upper surface of the door or other body in connection with which the handle is used. After the door has again assumed its horizontal position and the handle is released, it is apparent that it will automatically drop back into a seated position. If desired, the upper exposed side of the handle may be provided with a roughened surface so as to reduce the possibility of a person slipping thereon.

It is understood that the invention is not to be limited to the exact character of the top or head here shown, the essential feature being the provision of a substantially flattened head having a stem extending downwardly therefrom, a portion of which is tapered, preferably that portion directly integral under the head, the said tapered portion being adapted to be received by a corresponding tapered opening in a door, and the provision of a means carried by the stem to permit a limited movement thereof.

While there has here been shown but one of the preferred constructions, certain changes and modifications may be made thereof without departing from the spirit and scope of this invention.

Having thus described the invention, what I claim as new is:

1. A self-seating handle, particularly adapted for use on substantially horizontal doors, comprising a handle adapted to normally rest on the door, a stem extending downwardly therefrom, a portion of said

stem being tapered and adapted to be seated in an opening tapered to correspond therewith, and means carried by the stem to permit a limited movement of said handle to 45 permit the fingers to be inserted under the handle, the tapered stem portion and the seat forming a substantially water tight joint.

2. A self-seating door handle, adapted for 50 use on horizontal doors, comprising a tapered stem portion, a mushroom-shaped handle carried at one end, and a means carried at the other end thereof to permit a limited movement of the handle to permit 55 the insertion of the fingers under the handle, the tapered stem portion being adapted to normally rest on a correspondingly tapered seat of the door whereby a substantially water tight joint is formed, the outer 60 edge of the handle normally overlying the tapered portion, the said mushroom-shaped handle being normally substantially flush with the door.

3. In a device of the character described, 65 the combination of a door occupying a substantially horizontal position having an opening with tapered sides therein, and a self-seating door handle comprising a handle portion adapted to cover the upper part 70 of said opening, a stem extending downwardly from said handle, and having a tapered stem extending downwardly from said end seated in said opening forming a substantially water tight joint, and a removable means carried by said stem to permit a limited movement of the stem to 75 enable the fingers to be inserted under the handle and to prevent the withdrawal of said stem through said opening.

GEORGE W. KENNINGTON.
